UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

LINE-SWITCH.

1,257,338.

Specification of Letters Patent. Patented Feb. 26, 1918.

Application filed January 20, 1916. Serial No. 78,216.

To all whom it may concern:

Be it known that I, CHARLES L. GOODRUM, a citizen of the United States, residing at New York, in the county of New York and 5 State of New York, have invented certain new and useful Improvements in Line-Switches, of which the following is a full, clear, concise, and exact description.

This invention relates to automatic telephone systems, and particularly to means 10 for automatically connecting a calling line to an idle connecting circuit.

The principal object of the present invention resides in the provision of a switch of 15 this character, which employs but a single pair of movable contacts and which is operated by a small number of controlling magnets.

Any desired type of one movement switch 20 may be employed with the present invention. The present circuits, however, were especially designed for a rotating step-by-step switch. The drawing discloses a subscriber's individual line switch.

Assuming, now, that the subscriber at 25 substation A initiates a call by removing his receiver from its hook, a circuit will be completed from battery through the lower winding of line relay 1, upper armature and 30 back contact of cutoff relay 2, over the right side of the subscriber's line, through the substation apparatus thereof, back over the left side of the line, lower armature and back contact of relay 2, upper armature and contact 35 of magnet 3 and the upper winding of line relay 1 to ground. Line relay 1 will attract its armatures, completing a circuit from battery through magnet 3, switch motor magnet 4, its individual interrupter 5 and 40 the lower armature and contact of relay 1 to ground, thus causing the switch brushes 6 and 7 to make one step. The magnet 3 is made slow to release and holds up during the 45 hunting operation of the switch and until the completion of the conversation. This magnet, when energized, actuates a holding pawl to prevent release of the switch, and 50 interrupts, at its upper armature, the lead from the upper winding of relay 1 to the left side of the line during the testing operation.

In the present system the test contacts of 55 busy connecting circuits will be supplied with battery potential by a circuit extending through magnet 3, relay 2, and the back contact and upper armature of line relay 1 of

the line switch associated with the connecting circuit at one of its multiples. Thus, while the switch brushes are passing over the terminals of busy trunks, the line relay 1 of the seeking switch will be locked up by a 60 circuit extending from battery through the brush of the switch holding said trunk to the multiple test terminals of said trunk, and thence through brush 6 of the seeking switch, and the front contact and upper 65 armature of line relay 1 and the upper winding of said relay to ground; thus maintaining the relay energized and the circuit for the stepping magnet 4 closed until the contacts of an idle trunk are engaged. 70

Due to the operation of the individual interrupter 5, the switch motor magnet 4 will step the brushes 6 and 7 from contact to contact until the contacts of an idle trunk are reached. The test contacts of idle 75 trunks may be connected to ground in any usual and well-known manner. This ground may be connected at the back contact of the releasing magnet of the first selector switch, as shown in a Patent 1,245,436, issued November 6, 1917, to Edgar H. Clark. Thus, 80 when the switch engages an idle trunk, no battery potential will be on its test contact, and line relay 1 will retract its armatures and open the circuit for the stepping magnet 85 4, stopping the rotation of the switch. A circuit will also be completed from battery through relays 3 and 2 in series, back contact and upper armature of line relay 1 and test brush 6 to the lower or test contact of 90 the selected trunk, thus causing the trunk to test busy at its multiple contacts. The lower trunk conductor will be connected to ground as previously described, thus causing the energization of relay 2 and continuing the 95 energization of magnet 3. Relay 2, in attracting its armature, opens the circuit for the line relay 1, and extends the calling subscriber's line through to the brushes 6 and 7 of the line switch. At the close of conversation, the circuit through magnet 3 and relay 2 may be broken at the back contact of the releasing magnet of the connection switch, in the manner described in the 100 above-mentioned application. Relay 2, in deenergizing, disconnects the subscriber's line from brushes 6 and 7, and magnet 3 in deenergizing, allows the switch to return to its normal position and thereby places it in 105 readiness for another call. 110

It is obvious that the circuits herein disclosed are equally applicable to a line switch, the motor magnet of which is continuously energized during the movement of the 5 switch, the only modification necessary being the omission of the interrupter 5.

By the present structure, the necessity for the third or test wiper on the line switch is avoided, and but a single relay other than the 10 usual line and cut-off relays is required to control the operation of the switch. It will be noted that the line relay is operated: first, to start the switch, and then acts as a test relay to cause the selection of an idle trunk.

15 What is claimed is:

1. In a telephone system a subscriber's line, a relay, a group of trunk line terminal contacts, an automatic switch having a brush through which the talking circuit extends, a power magnet for causing said brush to move over said contacts, a circuit for said magnet extending through front contacts of said relay, means for operating said relay when a call is initiated upon said 20 line to close the circuit for said magnet, a circuit through said brush for maintaining said relay energized while said brush is in engagement with contacts of busy trunks, and means for deenergizing said relay to 25 open said magnet circuit when said brush engages the contact of an idle trunk.

2. In a telephone system a subscriber's line, a relay, a group of trunk line terminal contacts, an automatic switch having a brush 30 through which the talking circuit extends, a power magnet for causing said brush to move over said contacts, a circuit for said magnet extending through front contacts of said relay, a circuit for said relay including 35 both sides of said line in series closed when a call is initiated upon said line, and a locking circuit for said relay extending through a front contact thereof, said brush and the contacts of busy trunks.

45 3. In a telephone system a subscriber's line, a relay, a group of trunks having terminal contacts, an automatic switch having a brush through which the talking circuit extends, a power magnet for causing said 50 brush to move over said contacts, a circuit for said magnet extending through front contacts of said relay, a circuit for said relay including both sides of said line in series, means for closing said last circuit when 55 a call is initiated upon said line to operate said relay, a locking circuit for said relay, extending through a contact thereof, said brush and the terminal contacts of busy trunks and means for deenergizing said relay to open 60 said magnet circuit when said brush engages the contact of an idle trunk.

65 4. In a telephone system an incoming line comprising a pair of talking conductors, a switch having a pair of brushes in which said conductors terminate, a group of trunk

lines having terminal contacts, a power magnet for operating said switch to move said brushes over said contacts, a relay, a circuit for said magnet extending through contacts of said relay, means for operating said relay 70 when a call is initiated on said incoming line to close the circuit of said magnet and means responsive to the engagement of one of said brushes with the contact of an idle trunk for causing a reverse operation of said 75 relay to open said magnet circuit.

5. In a telephone system an incoming line including a pair of talking conductors, a switch having a pair of brushes at which said conductors terminate, a group of terminal contacts for outgoing lines, a magnet for controlling the operation of said switch to move said brushes over said contacts, a relay, a circuit for said magnet extending through front contacts of said relay, a circuit for said relay including both sides of said incoming line in series closed upon the initiation of a call upon said line and a locking circuit for said relay extending through a front contact thereof, one of said brushes 90 and the contacts of busy outgoing circuits.

6. In a telephone system a subscriber's line, a line relay, a group of trunk lines having terminal contacts, an automatic switch having a movable contact arranged to be 95 included in the talking circuit, a power magnet for causing said movable contact to traverse said terminal contacts, a circuit for said power magnet extending through contacts of said line relay, means to operate 100 said relay when said subscriber initiates a call to start said switch and means responsive to the engagement of said movable contact with the contact of an idle trunk to reversely operate said relay to stop said 105 switch.

7. In a telephone system a subscriber's line, a relay, a group of trunk lines having terminal contacts, an automatic switch having a brush arranged to be included in the 110 talking circuit, a power magnet for causing said brush to move over said contacts, a circuit for said magnet extending through front contacts of said relay, means for energizing said relay when a call is initiated on said 115 line to close the circuit for said magnet and means responsive to the engagement of said brush with the contact of an idle trunk for deenergizing said relay to open said magnet circuit.

8. In a telephone system a subscriber's line, a group of trunk lines having terminal contacts, an automatic switch having a brush, a power magnet for causing said brush to move over said contacts, a line relay, a circuit for said magnet extending through front contacts of said relay, a circuit for said relay including both sides of said line in series, means for closing said last circuit when a call is initiated upon 125 said line to operate said relay, a locking circuit for said relay, extending through a contact thereof, said brush and the terminal contacts of busy trunks and means for deenergizing said relay to open said magnet circuit.

65 130

said line to operate said relay, a locking circuit for said relay extending through a contact thereof, said brush and the terminal contacts of busy trunks, a cut-off relay, and 5 means for deenergizing said line relay to open said magnet circuit and close a circuit for said cut-off relay when said brush engages the contact of an idle trunk.

9. In a telephone system: an incoming line 10 including a pair of talking conductors, a switch having a pair of brushes at which said conductors terminate, a group of terminal contacts for outgoing lines, a magnet for causing the movement of said brushes 15 over said contacts, a relay, a circuit for said

magnet extending through front contacts of said relay, a circuit for said relay including both sides of said incoming line in series closed upon the initiation of a call upon said line, a locking circuit for said relay extending through a front contact thereof, one of said brushes and the contacts of busy outgoing lines and means responsive to the engagement of one of said brushes with the terminal of an idle outgoing line for interrupting said locking circuit. 20 25

In witness whereof, I hereunto subscribe my name this 19th day of January, A. D. 1916.

CHARLES L. GOODRUM.
